UNITED STATES PATENT OFFICE

109,253

DESIGN FOR AN AUTOMOBILE REAR FENDER

William H. Neely, Detroit, Mich., assignor to
Graham-Paige Motors Corporation, Detroit,
Mich., a corporation of Michigan

Application December 1, 1937, Serial No. 73,298

Term of patent 3½ years

To all whom it may concern:

Be it known that I, William H. Neely, a citizen of the United States, residing in Detroit, in the county of Wayne, State of Michigan, have invented a new, original, and ornamental Design for an Automobile Rear Fender, of which the following is a specification, reference being had to the accompanying drawing, forming a part thereof, wherein:

Fig. 1 is a view in perspective of the rear fender, showing my new design,

Fig. 2 is a view in side elevation of the same,
Fig. 3 is a view in rear elevation of the same,
and

Fig. 4 is a sectional view taken on the line
4—4 of Fig. 2 looking in the direction indicated
by the arrow.

I claim:

The ornamental design for an automobile rear
fender substantially as shown.

WILLIAM H. NEELY.
